DESIGN FOR A LACE COVER OR SIMILAR ARTICLE

Michael W. Saydah, New York, N. Y.

Application August 4, 1934, Serial No. 52,805

Term of patent 7 years

To all whom it may concern:

Be it known that I, MICHAEL W. SAYDAH, a citizen of the United States, residing in the county of Kings, city and State of New York, have invented a new, original, and ornamental Design for a Lace Cover or Similar Article, of which the following is a specification, reference being made to the accompanying drawing, forming a part thereof.

The figure is a plan view of a lace cover or similar article embodying my design.

The figure of the drawing is a plan view which shows substantially a quarter section of a lace cover, the other three-quarters being identical in design and arranged in proper relation to complete the cover.

I claim:

The ornamental design for a lace cover or similar article substantially as shown and described.

MICHAEL W. SAYDAH.
